(57) **CLAIM**

(22) Filed: **Nov. 1, 2000**

The ornamental design for a combined transmitter and receiver for a vehicle parking indicator sensor, as shown and described.

(51) LOC (7) Cl. **10-05**

DESCRIPTION

(52) U.S. Cl. **D10/109**

FIG. 1 is a front view of a combined transmitter and receiver for a vehicle parking indicator sensor according to our design, wherein the connector between the sensor and the indicator shown by broken lines is not part of the claimed design.

(58) **Field of Search** D10/104, 109,
